CLAIM

The ornamental design for a packaging box for a perfume bottle, as shown and described.

DESCRIPTION

FIG. 1 is a front elevational view of a packaging box for a perfume bottle showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and,

FIG. 7 is a perspective view in an open condition, the undisclosed portions of the box interior following the configuration of those shown.

The broken line showing of the perfume bottle in FIG. 7 is for illustrative purposes only and forms no part of the claimed design.
